UNITED STATES PATENT OFFICE.

CHARLES BILHARTZ, OF STRASBURG, FRANCE.

MACHINE FOR THE PRODUCTION OF TEXTILE FABRICS.

Application filed May 8, 1926, Serial No. 107,659, and in Switzerland May 21, 1925.

My invention relates to certain new and useful improvements in machines for producing fabrics of different kind, light fabrics such as tulle, bobbin net, fancy net, 5 woven lace, braids fancy gauze.

The main object of the present invention is to provide a machine for the production of such textile fabrics, which is simple in construction and which may be readily 10 adapted to any work.

Other objects of the invention relate to the provision of minor parts cooperating with the elements above noted and to details of construction, all of which will be more clearly 15 set forth in the following specification.

With the above objects in view the invention resides in the parts and combinations of parts hereinafter described, and particularly set forth in the claims appended here- 20 to.

An example of construction of the subject of the present invention is illustrated in the accompanying drawing, wherein:

Fig. 1 shows the machine in horizontal sec- 25 tion.

Fig. 2 is a side elevation.

Fig. 3 is a vertical cross section of the ma- 30 chine.

Figs. 4 and 5 show end elevations of the machine.

Figs. 6, 7, 8, 9, 10, 11 and 12 show details partly in section.

The machine illustrated is provided with two side frames 1, 2 in which a driving shaft 3 is rotatably mounted. The shaft 3, through the medium of chain gear 4, 5 drives a shaft 6 to which is keyed part of a worm wheel thread 7. The latter engages upon rotation of shaft 6 a worm wheel 8 which is keyed 40 to a shaft 9 at right angles to the shafts 3. On the rotation of the shaft 3 and 6 an intermittent motion is given to wheel 8 and there- 45 with to shaft 9. On the shaft 9 are mounted two discs 10, 11 (Fig. 10) in which are provided radial rows of holes 12. In the holes 12 are interchangeably mounted rollers 13. The discs 10, 11 actuate by means of their rollers 13 two horizontally disposed bars 14, 15 which are slidably mounted in 50 the machine frame 1, 2 independently of each other. The bars 14, 15 are at the same level parallel one to the other; each is provided with an arm 16, projecting upwardly into the path of the rollers 13 and each is under 55 the action of a spring 17 which tends to draw the corresponding bar 14, 15 toward the

right Fig. 2, so that they bear against the rollers 13. On the rotation of the shaft 9 the two bars 14, 15 are moved more or less against the action of the spring 17 according to the position of the driving members 13 at any time. The bars 14, 15 are provided with slots 17 at right angles to the longitudinal direction, which end towards the edges of the bars 14, 15, which are turned towards one another. In these slots 17 are mounted bobbin carriers 18 (Figs. 7 and 8) so as to be readily movable. Each bobbin carrier carries a yarn bobbin 19 (Fig. 8). Further, there is provided for each bobbin carrier 18 or for 70 each slot 17 an actuating rod 20, which is movably mounted on the machine frame. The rods 20 are arranged in two rows to both sides of the bars 14, 15, a rod being always movably mounted adjacent each slot 17 in 75 the direction of these slots 17. For each row of rods 20 there are provided pusher cylinders 22, 23. These pusher cylinders 22, 23 are hollow and are provided with grooves 80 in the longitudinal direction, for example eight grooves in which are fitted bars or pasteboard cards, 24 which are perforated in a similar manner as in jacquard apparatus, according to a predetermined pattern of the fabric to be manufactured. The cylinders 22, 23 are rotatably and slidably mounted in horizontal slots of the machine frame 1, 2 by means of pivots 4, 5; they run parallel to the rows of rods 2 so that when moving one cylinder or the other towards the rods 20 90 those rods of a row are moved inwardly which cannot pass into a hole in the jacquard card 24. The perforating of the jacquard card 24 is effected as in jacquard apparatus, according to a predetermined pattern of the 95 fabric to be produced. For giving the pushing cylinders 22, 23 an intermittent rotary motion about their own axes and for moving the cylinders 22, 23 in a horizontal direction there are rotatably mounted on the two 100 sides of the machine frame 1, 2 two shafts 27, 28 which are driven from the main driving shaft 3 by means of toothed wheels 30 and an intermediate shaft 31. The shaft 3 is provided with two bevel gears 33 driving on said intermediate shafts 31. On each of the shafts 27, 28 there are keyed two drums 40, 41 with cam grooves cut into their circumference. Driving pins 42 which are rigidly connected to links 44 mesh with said 105 grooves. These links 44 are pivotally connected to the pivot pins 45 of the pushing 110

cylinders 22, 23. The shape of the grooves in the drums 40, 41 is such that at each complete revolution of one of the shafts 27, 28 the pushing cylinders 22, 23 are moved fully 5 inwards towards the corresponding bar 14 or 15 and again returned to the initial position. For this purpose the grooves of the two drums 40, 41 are so arranged with reference to each other that while one pushing cylinder 10 is moved inwardly the other pushing cylinder is moved simultaneously outwardly. The two pushing cylinders 22, 23 might also be simultaneously moved inwards and again return simultaneously by forming the 15 grooves in the drums 40, 41 accordingly. Only in this case the bobbin carriers 19 must be arranged in alternate slots 17 of the bars 14, 15 that an occupied slot 17 of one bar will always be opposite an empty slot 17 of 20 the other bar 14, or 15 in each working position. Consequently as a maximum only half of all the slots 17 are fitted with bobbin carriers 19. To the pivots 45 of the pushing cylinders 22, 23 there is also connected a bar 25 47 (Figs. 3 and 11) by means of links 44 (Fig. 11). The rods 20 are provided with collars 46 with which the bars 47 engage. The bars 47 are reciprocated together with the pushing cylinders 22, 23, and they bring 30 the rods 20 back to their initial position. To rotate the pushing cylinders 22, 23 there is secured to one pivot 45 of each cylinder 22, 23, a worm wheel 48. A driving element 49 forming part of a worm thread and rigidly 35 mounted on the shaft 31 engages said wheel 48 once each rotation of shaft 31. The rotation of the pivot 45 and therewith the rotation of the pushing cylinders 22, 23 is always effected when the cylinders 22, 23 have 40 reached their outermost position or when they are not in engagement with the rods.

Above the bars 14, 15 there is mounted in the frame 1, 2 a roller 51 for the reception of the fabric produced. This roller is advanced by a known apparatus, not illustrated and described in detail, as the production of the fabric proceeds. Underneath the bars 45 14, 15 there are also provided warp beams 52 from which the warp is guided vertically 50 upwards by known guide means between the bars 14, 15.

In order to produce fabric, the bobbin carriers 18 are pushed from the bar 14 into the other bar 15 and vice versa, and this 55 movement of the bobbin carriers 18 is effected according to the perforations of the jacquard cards 24 which are secured to the cylinders 22, 23. By this movement of the bobbin carriers 18 from one bar 14 to the other 60 bar 15 and by the simultaneous movement of the bars 14, 15 parallel one to the other the threads from the separate bobbins 19 are

caused to be looped. The bars 14, 15 according to the adjustment of the rollers 13 can be relatively displaced by one or more 65 slots 17.

In order to produce a twist connection or a thread looping, as is the case when weaving tulle, a bobbin carrier 18 is fitted as follows: Where there is a bobbin carrier 18 in a slot 17 of a bar, the opposite slot 17 in the other bar is empty. Then all the bobbin carriers 18 are moved from one bar 14 into the other 15 or vice versa. Hereupon the bobbin carriers 18 are again moved into the other bar 14 or 15. Operating further in this manner two bobbin carriers 18 would always follow one another in a circle and the two threads would be twisted. By moving the bars 14, 15 laterally through different distances and by alternately moving the bobbin carriers 18 it is possible that the same two threads will not always be twisted together but that always a different adjacent thread is twisted in and finally all the 85 threads have been interlooped, as in a net. 90

What I wish to secure by U. S. Letters Patent is:

1. Machine for the production of textile fabrics, comprising in combination, a fabric beam, an automatic take-up motion, two bars relatively adjustable, yarn carriers, guides on said bars for said carriers, means to adjust the two bars relatively, said means comprising for each bar a disc, advanced in steps, 95 having adjustable driving members, which can move the bar to a predetermined extent, and active to resist such movement, means for moving the yarn carriers from one bar to the other for the purpose of looping the 100 threads leading from the yarn carriers to the fabric beam selectively together and if desired with warp and warp threads.

2. Machine for the production of textile fabrics, comprising, in combination, a fabric beam, an automatic take-up motion, two bars relatively adjustable, yarn carriers, guides on said bars for said carriers, means to adjust the two bars relatively, said means comprising for each bar a disc advanced in 105 steps and having adjustable driving members, arranged to move the bar a predetermined extent and a spring active to resist such movement, means for moving the yarn carriers from one bar to the other for the 110 purpose of looping the threads leading from the yarn carriers to the fabric beam selectively together, the last said means comprising a jacquard apparatus provided for each bar and arranged to adjust all the 115 yarn carriers according to the pattern.

In witness whereof I affix my signature.

CHARLES BILHARTZ.
